THE S. R. SMYTHE COMPANY, OF PITTSBURG, PENNSYLVANIA, A CORPORATION OF
WEST VIRGINIA.

REVERSING-VALVE.

1,000,629.

Specification of Letters Patent. Patented Aug. 15, 1911.

Application filed April 21, 1911. Serial No. 622,479.

To all whom it may concern:

Be it known that I, HERMANN E. SCHILD, a citizen of the United States, residing at Pittsburg, in the county of Allegheny and 5 State of Pennsylvania, have invented new and useful Improvements in Reversing-Valves, of which the following is a specification.

My invention relates to gas reversing 10 valves designed particularly for use with regenerative furnaces, and is an improvement on the reversing valve described and claimed in Letters Patent No. 804,505 granted to me November 14, 1905.

15 The object of the present invention is to bring all the elements of a reversing valve into a unit, whereby the various connections can be accomplished by the rotation of a single structure, effecting a considerable 20 saving in space and cost.

Referring to the accompanying drawings, Figure 1 is a plan of my improved reversing valve with the valve f^8 and the valve-chamber F removed. Fig. 2 is a horizontal section on the line II-II of Figs. 3 and 4. 25 Figs. 3 and 4 are vertical sections on the lines III-III and IV-IV, respectively, of Figs. 1 and 2, Fig. 4 showing the air-valve mechanism in end elevation. Fig. 5 is a 30 plan of the base-plate, and the passages beneath the level thereof. Fig. 6 is a vertical section on the line VI-VI, Fig. 5.

A horizontal base-plate A of iron or steel is mounted on a suitable foundation or sub-35 structure B and has therein the central circular port or opening a surrounded by the four ports or openings a' , a^2 , a^3 , a^4 , equally distant from the opening a . The opening a' is diametrically opposite the opening a^4 , 40 and the opening a^2 is diametrically opposite the opening a^3 . The openings a' and a^2 are sixty degrees apart, as also are the openings a^3 and a^4 , leaving one hundred and twenty degrees between the openings a' and a^2 , 45 and between the openings a^2 and a^4 . The sub-structure B has the central stack flue b leading from the opening a downwardly and then horizontally, and the four flues b' , b^2 , b^3 , b^4 leading respectively downwardly and then horizontally from the openings a' , a^2 , a^3 , a^4 .

50 The circular horizontal water-pan or water-cooled valve-plate C is seated on the base-plate A and is in axial alinement with the center of the opening b . The pan C

has an annular depending hub c^7 fitting in an annular depression in the plate A to prevent the pan from sliding out of said axial alinement. The pan C has five upwardly flanged openings c , c' , c^2 , c^3 , c^4 , c^5 , c^6 60 arranged sixty degrees apart, the opening c permanently registering with the opening a , and four of the openings c' , c^2 , c^3 , c^4 , c^5 , c^6 registering at a time with the openings a' , a^2 , a^3 , a^4 as will be explained presently. 65 The pan C has an outer upstanding flange c^8 , which with the flanges aforesaid form a water pan to keep the pan and adjacent parts from burning out.

The pan C has therein the short radial 70 ribs c^9 extending inwardly from the outer flange c^8 and upwardly slightly from the bottom of the pan. On these ribs rests the lower edge of the hood D, which is, in general, dome-shaped, its lower edge resting 75 beneath the surface of the water in the pan to form a gas-seal. The hood has the opening d centrally over the opening c ; the openings d^2 and d^5 in the form of tubes surrounding the flanges of the openings c^2 and c^5 , respectively, and having their inner portions resting on the ribs c^{10} below the water in the pan C. The upper ends of the tubes d^2 and d^5 open into the external atmosphere. The hood D has another opening or tube d^4 , 80 having its lower end surrounding the flange of the opening c^4 and resting on the ribs c^9 and c^{10} below the water level in the pan C. 85

On the hood D, I place the box E having a central bottom opening e^7 registering with the opening d ; an opening e^4 registering with the upper end of the tubular opening d^4 ; and a central upper opening e in axial alinement with the openings a , b , c , and d . Normally the opening e^7 is closed by the 90 cover d^8 . The opening e is surrounded by two concentric flanges forming a water-trough, into which the lower edge of the flange f^7 of the gas-chamber F extends to form a gas-seal. The bottom plate f^{12} of 95 the chamber F is provided with the valve seat or opening f centrally over the opening e .

f^8 is a valve suspended from the reciprocal stem f^9 , by which the flow of gas 100 through the opening f may be regulated or stopped. The chamber F is stationary and rests on the beams f^{10} supported on the posts f^{11} .

A horizontal rock-shaft g has bearings in 110

the ears f^{13} on the bottom f^{12} and is provided with a central arm g' , to which is secured the chain g^2 for raising, lowering, and holding the said arm. The ends of the 5 shaft g are provided with the arms g^3 and g^4 , connected to the valves or covers g^5 and g^6 by the links g^7 . The cover g^5 is centrally over the opening d^2 when the parts are as shown on the drawing; and the cover 10 g^6 is centrally over the opening d^5 when the pan C and parts supported thereby have been rotated sixty degrees in the direction indicated by the arrow h , Figs. 1 and 2. The pan C may be rotated by various means 15 but I have shown the worm I gearing with teeth on the periphery of the pan. The worm is mounted on the shaft i driven by any suitable mechanism.

The parts being as shown on the drawings, 20 gas passes from the chamber F, connected to any suitable source of gas-supply, through the valve opening f , the opening e , the gas-box E, the openings e^4 , d^4 , c^4 and a^4 to the flue b^4 , which, we may assume, conducts the 25 gas to the gas side of a hot regenerator chamber, whence it passes to a furnace, in which it is burned with air which, flowing through the openings d^2 , c^2 , and a^2 , passes into the flue b^2 , leading to the air side of the regenerator chamber and thence, it is assumed, 30 to the furnace. The waste gases pass from the furnace through another set of regenerators from which the gases return to the hood D in two paths, one path being through 35 the flue b' , the openings a' and c' , and the other path being through the flue b^3 and the openings a^3 and c^3 . From the hood D the waste gases pass to the stack-flue through 40 the openings c and a . The elongated arrows on Figs. 1-4 show the direction of the air, gas, and waste gases.

When it is desired to reverse the flow of the air and gases, the shaft i is actuated to rotate the pan C and parts supported thereby sixty degrees with the arrow h , whereupon the opening c' registers with the opening a^2 , the opening c^6 with the opening a^4 , the opening c^4 with the opening a^3 , the opening c^5 with the opening a' , and when the 45 opening c^2 passes on to a dead or closed space on the plate A between the openings a^2 and a^4 , and the opening c^3 passes on to a dead or closed space on the plate A between the openings a' and a^3 , the air-tube d^5 passes underneath the cover g^6 and the air-tube d^2 passes from under the cover g^5 . It will be seen that the gas now passes as before through the opening c^4 , from 50 which it enters the flue b^3 , and that the air passes down the air-tube d^5 and through the openings c^5 into the flue b' . The air and gas after being burned in the furnace 55 return to the dome D as waste products by way of the flues b^2 and b^4 . From the dome

the waste gases enter the stack-opening c 65 and the stack-flue b . By returning the parts to the positions shown on the drawings the gases will be again reversed so as to assume their former courses. The valves or covers g^5 , g^6 may, by the chain g^2 , be adjusted up 70 or down to regulate the supply of air.

In case it is desired to heat the stack on starting the furnace and regenerators, the cover d^8 may be removed from the opening e^7 by removing the cover e^9 from the end 75 of the box E and inserting a suitable tool. The gas can then pass directly from the box E into the hood D and thence into the stack-flue b where it is burned to preheat the stack.

The gas passages c^4 , d^4 , e^4 , e , f , register with the flue b^4 or b^3 ; the air-tube d^2 registers with the flue b^2 , or the air-tube d^5 registers with the flue b' ; and the stack-flue communicates with the flues b' and b^3 , or the flues 85 b^2 and b^4 , the flues b' — b^4 , when acting as waste-flues, communicating with the chamber within the hood or dome D.

I claim—

1. In a reversing valve, a rotary valve- 90 plate having a central stack-port and a circular series of six ports arranged 60° apart around the stack port, a hood connected gas-tight to the valve-plate and inclosing the stack-port and the alternate ports of the 95 said six ports, a gas-supply passage connected to one of the remaining ports in the valve-plate, and an air-supply tube connected to each of the two remaining ports in the valve plate, a stack registering with 100 the stack port, a pair of convertible air and waste flues 60° apart, and a pair of convertible gas and waste flues 60° apart and diametrically opposite the air and waste flues, one of the air-ports and the intermediate 105 waste-port registering with the air and waste flues, and the gas passage and one of the remaining waste-ports registering with the gas and waste flues, and means for rotating the valve-plate.

2. In a reversing valve, a stack flue, a pair of convertible air and waste flues and a pair of convertible gas and waste flues arranged around the stack flue, a rotary valve-plate having a central waste-port, a 115 pair of air ports, a gas-port, and waste ports between the air-ports, and between each air-port and the gas-port, the ports being spaced so that, when one of the air-ports registers with one of the air and waste 120 flues, the intermediate waste-port registers with the remaining air and waste flue, and, when the gas-port registers with one of the gas and waste flues, one of the waste-ports at either side of the gas-port registers with 125 the remaining gas and waste flue, a hood connected gas-tight to the valve-plate and inclosing the waste-ports and the stack-port,

a gas-supply passage connected to the gas-port, an air-tube connected to each air-port, and means for rotating the valve-plate.

3. In a reversing valve, a pair of convertible air and waste flues and a pair of convertible gas and waste flues, a stack flue centrally arranged with respect to the said pair of flues, a valve-plate having rotation transversely of said flues, a hood sealed to the valve-plate and covering the stack flue, and means to oscillate the valve-plate to two positions, the hood and valve-plate having passages disposed to admit air alternately to the said air-flues at the two said 10 positions of the valve-plate, the valve-plate

having openings disposed so as to lead the waste-gases alternately from the waste-gas flues to the interior of the hood at the two said positions of the valve-plate, and the valve-plate and hood having a gas inlet disposed so as to admit gas alternately to the gas flues at the two said positions of the valve-plate. 20

Signed at Pittsburg, Pa., this 19th day of April, A. D. 1911.
